US00D622811S

(12) **United States Design Patent**
Cooper et al.

(10) **Patent No.:** US D622,811 S
(45) **Date of Patent:** ** Aug. 31, 2010

(54) **APPARATUS FOR USE IN SELF-TANNING**

(75) Inventors: **Linda G. Cooper**, 3225 Turtle Creek,
Suite 1111, Dallas, TX (US) 75219;
George Carter, Garland, TX (US);
Myles T. Christensen, Pueblo West, CO
(US)

(73) Assignee: **Linda G. Cooper**, Dallas, TX (US)

(**) Term: **14 Years**

(21) Appl. No.: **29/333,220**

(22) Filed: **Mar. 4, 2009**

(51) **LOC (9) Cl.** 23-01

(52) **U.S. Cl.** D23/225

(58) **Field of Classification Search** D6/566,
D6/512; D9/448, 682, 685, 686; 222/78-79,
222/174, 153.11, 323, 402.15, 473

(57) **CLAIM**

The ornamental design for the apparatus for use in self-tanning, as shown and described.

DESCRIPTION

FIG. 1 is a front perspective view of the apparatus for use in self-tanning showing our new design;

FIG. 2 is a front elevational view of the apparatus for use in self-tanning;

FIG. 3 is a side elevational view of the apparatus for use in self-tanning;

FIG. 4 is a rear elevational view of the apparatus for use in self-tanning;

FIG. 5 is a top plan view of the apparatus for use in self-tanning; and,

FIG. 6 is a bottom plan view of the apparatus for use in self-tanning.

Any broken line illustration of environmental structure in the drawings is not part of the design sought to be patented.
